PLASTIC COVERED NONRIGID WINGED BOX KITE

Wilbur E. Green, Houston, Tex.

Application November 17, 1952, Serial No. 320,927

2 Claims. (Cl. 244—153)

This invention relates to a collapsible kite and has for its particular object the provision of a kite of the character to be described which employs means for preventing damage to the sails, spars and sticks of the kite when subjected to stresses during operative flying.

A further object of this invention is to provide a collapsible kite which may be readily constructed from various readily available material and which employs a sail constructed from a thin film of suitable plastic material which is adhesively bonded to the vertically extending sticks.

The construction of this invention features the use of a cross spar which has either integrally molded therewith or attached thereto substantially L-shaped clips which rigidly engage the vertical sticks. The clips are adapted to embrace the sticks thus holding the sails onto the sticks reinforcing the binding relationship between the sails and the sticks.

Another feature of the invention resides in the means for resiliently securing the sails to the end of the cross spar. The cross spar is slotted to receive resilient members or bands which are engaged between the bifurcations formed in the ends of the spar by the slots.

Still further objects and features of this invention reside in the provision of a kite that is strong, durable, highly efficient in flying, simple in construction and manufacture, and which is highly pleasing in appearance.

These together with the various ancillary objects of the invention which will become apparent as the following description proceeds, are attained by this kite, a preferred embodiment of which has been illustrated in the accompanying drawings, by way of example only, wherein:

Figure 1 is front elevational view of the kite comprising the present invention;

Figure 2 is a horizontal sectional view as taken along the plane of line 2—2 of Figure 1, and being drawn in an enlarged scale for greater clarity;

Figure 3 is a vertical sectional view as taken along the plane of line 3—3 in Figure 1 showing the construction in detail of the angularly disposed jib sails of conventional construction;

Figure 4 is a perspective view of the kite comprising the present invention showing the relationship of the varying parts with greatest clarity;

Figure 5 is a schematic diagram showing the manner in which the sticks and the cross spar are secured to each other; and,

Figure 6 is a perspective detail showing the means used for resiliently securing the sails to the cross spar.

With continuing reference to the accompanying drawings wherein like reference numerals designate similar parts throughout the various views, reference numeral 10 generally designates a vertically extending stick and reference numeral 12 generally designates another stick of the same nature and character. The sticks 10 and 12 may readily be formed of wood or like material but can equally easily be constructed from any suitable plastic material such as polystyrene, or any other suitable synthetic resin. Bonded to the sticks 10 and 12 are triangular sails 14 and 16 which have secured at their apexes substantially U-shaped members 18 and 20 for purpose to be henceforth explained.

Bonded or otherwise secured in any convenient manner to the sticks 10 and 12 are jib sails 24 and 26 which are also bonded to a vertically extending stick 28. The triangular jib sails are of conventional construction and

are readily made from the same type of material from which the sails 14 and 16 are constructed. The bridle 30 is secured to the stick 28 and the line 32 may be readily attached to the bridle 30 at the optimum point of aerodynamic balance.

A cross spar 34 is provided and may readily be molded from any suitable plastic material or may, if desired, be constructed from wood or a light metal. Substantially L-shaped clips 36 and 38 are preferably integrally molded with the cross spar 34 and extend in opposite directions. The clips 36 and 38 are adapted to resiliently embrace the sticks 10 and 12 while also embracing the sails 14 and 16 while they surround the sticks 10 and 12. This construction can be best seen in Figure 2. In this manner of securing the cross spar to the sails, the usual stresses caused while flying will not tend to cause the cross spar 34 to tear the sails 14. Rather, the cross spar 34 will in fact reinforce the sails at the point of contact.

The cross spar 34 is provided with slots 40 and 42 which form bifurcated ends for the cross spar 34. Resilient bands 44 are secured to the U-shaped members 18 and 20 and are adapted to be received within the slots 40 and 42. The bands 44 thus form a resilient connection between the sails 14 and 16 and the cross spar 34 to insure stability in flight. The elasticity of the resilient bands 44 provides a slackening and tightening flexibility of the wings 14 and 16 thus lessening or increasing the wing surface resistance to various intensities of wind.

In the construction of this invention, the plastic wings 14 and 16 have no rigid attachment except at the point where bonded to the sticks 10 and 12. Thus, stability in flight is maintained in varying wind intensities by the drag or pull of the flapping or fluttering feathering unreinforced edges of the plastic film wings 14 and 16. Furthermore, the reinforcing provided by the cross spar 34 is in direct opposition to those devices which have been previously constructed. The L-shaped clips 36 and 38 substantially reinforce the wings 14 and 16 at their points of juncture with the sticks 10 and 12 rather than oppose such juncture.

Since from the foregoing, the construction and advantages of this collapsible kite are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications and equivalents may be readily resorted to that fall within the scope of the appended claims.

What is claimed as new is as follows:

1. A collapsible kite comprising a pair of parallel sticks, triangular sails attached to said sticks, a cross spar spacing said sticks apart, opposed substantially L-shaped clips on said spar, said sails substantially embracing said sticks, said clips embracing said sticks and embracingly engaging said sails to reinforce the attachment between said sails and said sticks, means securing said sails to said spar including substantially U-shaped members secured to said sails, and resilient members attached to said U-shaped members, said spar having slots in the ends thereof, said resilient members being received in said slots to provide an adjusted wing surface resistance to various intensities of wind.

2. A collapsible kite comprising a pair of parallel sticks, triangular sails of film-like material bonded to said sticks, a cross spar spacing said sticks apart, opposed substantially L-shaped clips integrally formed with said spar, said sails substantially embracing said sticks, said clips embracing said sticks and embracingly engaging said sails to reinforce the bond between said sails and said sticks, means securing said sails to said spar including substantially U-shaped members secured to said sails, and resilient members attached to said U-shaped members, said spar having slots in the ends thereof, said resilient members being received in said slots to provide an adjusted wing surface resistance to various intensities of wind, said film-like sails having unreinforced edges to

maintain stability in flight even when subjected to the various intensities of wind.
